UNITED STATES PATENT OFFICE.

VIRGINIA F. BEEDE, OF STOCKTON, CALIFORNIA.

HAIR-RESTORATIVE.

SPECIFICATION forming part of Letters Patent No. 766,984, dated August 9, 1904.

Application filed November 17, 1902. Serial No. 131,759. (No specimens.)

To all whom it may concern:

Be it known that I, VIRGINIA F. BEEDE, a citizen of the United States, residing at Stockton, in the county of San Joaquin and State 5 of California, have invented certain new and useful Improvements in Compositions for Treating the Hair, of which the following is a specification.

My invention relates to medical compounds, 10 and more especially to compositions for treating the hair, partly to restore its natural color, but which may also be used for cleansing purposes and as a tonic for preserving the hair and scalp in good and healthful condition. 15 The object of the invention is to provide an effective composition for the purposes above mentioned which contains no acids or other substances of a nature injurious to the hair, scalp, or brain and has no effect upon any part 20 of the system excepting those which it is intended to produce.

In making my compound I proceed as follows, using the ingredients and substantially the proportions hereinafter stated: One and 25 one-half (1½) ounces of henna-leaves, finely ground, are macerated with twelve (12) ounces of cold water for about four (4) hours. The mixture is then placed in a porcelain vessel, boiled for about fifteen (15) minutes, and then 30 allowed to cool. When cold, it is placed in any suitable percolator and sufficient cold water added to make the percolate measure thirteen (13) ounces. This percolate is then mixed with the following ingredients: aromatic spir- 35 its of ammonia, two (2) drams; Fowler's solution of arsenic, two (2) drams; alcohol, four (4) drams, and oil of rose-geranium, two (2) drops. After this mixture the compound is ready for use. The method of applying and 40 using it is as follows: The hair is first washed

clean and dried, after which the composition is applied to all parts of the hair, preferably with a small brush, and allowed to dry. The compound being perfectly harmless and producing no injurious effects of any kind, it can 45 be applied to the hair three or four times a day, the hair being allowed to dry in the intervals. No extreme or special care need be used beyond that required for making the application to all parts of the hair, since if the 50 composition stains the skin such stains can be immediately removed with soap and water.

Besides being effective for the described purpose, with natural hair my compound can also be used for coloring artificial hair, such 55 as switches and false fronts, such artificial hair being simply washed and dried and then soaked in the compound.

Having thus fully described my invention, what I claim as new, and desire to secure by 60 Letters Patent, is—

1. A compound for the described purposes, composed of henna-leaves, aromatic spirits of ammonia and arsenic, in the proportion substantially as described. 65
2. A compound for the described purposes, composed of henna-leaves, ammonia, and arsenic, with alcohol as a preservative.
3. A compound for the described purposes, composed of henna-leaves, aromatic spirits of 70 ammonia, Fowler's solution, alcohol, and oil of rose-geranium.

In testimony whereof I have affixed my signature, in presence of two witnesses, this 10th day of July, 1902.

VIRGINIA F. BEEDE.

Witnesses:

Gus. G. GRANT,
W. M. S. BEEDE.
